Primary Examiner — Susan Bennett Hattan*Assistant Examiner* — Lauren D McVey(74) *Attorney, Agent, or Firm* — Ewers & Hasselmann PLLC(57) **CLAIM**

The ornamental design for a demonstration tool, as shown and described.

DESCRIPTION

FIG. 1 is a perspective view of a demonstration tool showing my new design;

FIG. 2 is a front view of the demonstration tool of FIG. 1; FIG. 3 is a rear view of the demonstration tool of FIG. 1; FIG. 4 is a left-side view of the demonstration tool of FIG. 1;

FIG. 5 is a right-side view of the demonstration tool of FIG. 1;

FIG. 6 is a top plan view of the demonstration tool of FIG. 1; and,

FIG. 7 is a bottom view of the demonstration tool of FIG. 1. The broken lines depict portions of the demonstration tool that form no part of the claimed design.

1 Claim, 7 Drawing Sheets(56)
